Primary Examiner—Mitchell I Siegel**Attorney, Agent, or Firm**—Kelly Bauersfeld Lowry & Kelley, LLP**[57]****CLAIM**

The ornamental design for a iron-type head for a golf club, as shown and described.

DESCRIPTION

FIG. 1 is a rear perspective view showing an iron-type head for a golf club embodying the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a sectional view taken along the line 8—8 of FIG. 3;

FIG. 9 is an enlarged sectional view taken along the line 9—9 of FIG. 3;

FIG. 10 is a rear perspective view showing the rear side of an alternative embodiment of my design;

FIG. 11 is a rear elevational view of the alternative embodiment shown in FIG. 10;

FIG. 12 is a sectional view taken along the line 12—12 of FIG. 11; and,

FIG. 13 is an enlarged sectional view taken along the line 13—13 of FIG. 11.

The undisclosed sides of the second embodiment is identical to those disclosed in the first embodiment.
